Attorney.

UNITED STATES PATENT OFFICE.

EDWIN S. WOODS, OF CHICAGO, ILLINOIS.

CAR-TRUCK.

SPECIFICATION forming part of Letters Patent No. 696,617, dated April 1, 1902.

Application filed July 27, 1901. Serial No. 69,876. (No model.)

To all whom it may concern:

Be it known that I, EDWIN S. WOODS, a citizen of the United States of America, and a resident of Chicago, in the county of Cook and State of Illinois, have invented certain new and useful Improvements in Car-Trucks, of which the following is a specification.

The present invention relates to railway-car trucks, and more especially to that particular type of car-truck which forms the subject-matter of my prior patent, No. 655,386, dated August 7, 1900, and in which the springs affording the required yielding support for the car-body are arranged between the bolster and the side frames of the car-truck.

The present improvement has for its object to provide a substantial and efficient construction and arrangement of parts in the above-described type of car-trucks in which a free and independent lateral movement of the car-wheels and axles with relation to the truck to compensate for irregularities in the track is attained and with which a return of the parts to a normal position after a lateral movement in either direction is accomplished in a positive and certain manner, all as will herein-after more fully appear, and be more particularly pointed out in the claims.

In the accompanying drawings, illustrative of the present invention, Figure 1 is a fragmentary side elevation of a car-truck embodying the present improvements; Fig. 2, an enlarged detail side elevation with parts in section; Fig. 3, an enlarged central transverse section mainly on line xx , Fig. 2.

Similar numerals of reference indicate like parts in the several views.

Referring to the drawings, 1 represents a counterpart half of the side frame or pedestal portion of a car-truck provided with the usual open-bottomed recess, in which the axle-box 2 is arranged, the lower end of the frame members forming such recess being tied together by the usual removable tie-bar 3, as shown. As so arranged the axle-box is free to have lateral movement within a prescribed range in said recess to compensate for irregularities in the track and the consequent independent lateral movements of the car-wheels and axle.

4 is the car-truck bolster, the ends of which are adapted to fit in and interlock within a

centrally-arranged rectangular guide-opening in the side frame or pedestal 1 and have a limited vertical movement therein. 55

5 represents a spring, of which any desired number may be employed, arranged between the under side of the bolster end and the portion of the side frame 1 forming the bottom of the aforesaid centrally-arranged opening 60 and affording a yielding support for the said bolster and the car-body carried thereby.

6 is a track member, preferably in the form of a removable plate, arranged in a receiving-recess therefor in the top surface of the axle-box 2, but which may constitute an integral part of such axle-box, if so desired, without departing from the spirit of the present invention.

7 is a crown-piece member secured to the upper or crown portion of the recess in the side frame which receives the axle-box and having a separated vertical relation above the track member or plate 6, above described.

8 represents a counterpart set of bearing-rollers interposed between the opposed faces of the crown-piece 7 and the track-plate 6 and arranged in a direction longitudinal of the side frame 1 of the car-truck. Such rollers are adapted to form a frictionless bearing, 80 upon which the axle-box track-plate 6 can move independent of the crown-piece 7 in a lateral movement of the car-axle and car-axle box with relation to the side frame 1.

In the present improved construction the 85 opposite faces of the track-plate 6 and crown-piece 7 are formed with counterpart curved or dished recesses 9 and 10, which constitute bearing-surfaces for the rollers 8 in their rolling movement, and which recesses are individual to its respective roller. By such curved or dished construction of the bearing surfaces or recesses 9 and 10 a return of the parts to a normal central position with relation to each other is assured when the lateral force 95 by which they were displaced therefrom ceases.

In the construction shown the respective recesses 9 and 10 are separated by a central stop-rib or partition 11 and are provided with 100 outer or marginal stop flanges or ribs 12, which afford means to limit the lateral movement of the car-axle and box in either direction to a prescribed limit, and as so construct-

ed a prescribed and limited lateral movement is afforded to the axle-box with relation to the side frame of the truck to prevent undue pressure of the flanges of the car-wheel against the track-rails and the undue wear and liability to fracture of said wheel-flanges under the heavy loads usually carried.

The present improved construction and arrangement of parts affords a very strong and durable connection of parts in that the bearing upon the rollers is a direct one.

Having thus fully described my said invention, what I claim as new, and desire to secure by Letters Patent, is—

15. 1. The combination with a pedestal car-truck and its axle-boxes, of crown-pieces attached to the side frame in a direct vertical plane above the axle-boxes, and rollers directly interposed between said crown-pieces and the top of the axle-boxes and adapted to afford independent lateral movement to such axle-boxes, substantially as set forth.
20. 2. The combination with a pedestal car-truck and its axle-boxes, of crown-pieces attached to the side frame in a direct vertical plane above the axle-boxes, and rollers directly interposed between said crown-pieces and the top of the axle-boxes, the opposed bearing-surfaces for such rollers having a curved or dished form adapted to afford lateral and self-centering movements to the axle-boxes, substantially as set forth.
25. 3. The combination with a pedestal car-truck and its axle-boxes, of crown-pieces attached to the side frame in a direct vertical plane above the axle-boxes, and rollers directly interposed between said crown-pieces and the top of the axle-boxes, the opposed bearing-surfaces for such rollers having a curved or dished form adapted to afford lateral and self-centering movements to the axle-boxes, and end flanges constituting stops, substantially as set forth.
30. 4. The combination with a pedestal car-truck and its axle-boxes, of crown-pieces attached to the side frame in a direct vertical plane above the axle-boxes, and a series of rollers directly interposed between each crown-piece and axle-box and adapted to afford independent lateral movement to the axle-boxes, substantially as set forth.
35. 5. The combination with a pedestal car-truck and its axle-boxes, of crown-pieces attached to the side frame in a direct vertical plane above the axle-boxes, and a series of rollers directly interposed between each crown-piece and axle-box, the opposed bearing-surfaces for such rollers having a dished or curved form adapted to afford lateral and

self-centering movements to the axle-boxes, 60 substantially as set forth.

6. The combination with a pedestal car-truck and its axle-boxes, of crown-pieces attached to the side frame in a direct vertical plane above the axle-boxes, and a series of 65 rollers directly interposed between each crown-piece and axle-box, the opposed bearing-surfaces for such rollers having a dished or curved form adapted to afford lateral and self-centering movements to the axle-boxes, 70 and end flanges constituting stops, substantially as set forth.

7. The combination with a pedestal car-truck and its axle-boxes, of crown-pieces attached to the side frame in a direct vertical 75 plane above the axle-boxes, track-plates secured to the tops of the axle-boxes, and rollers directly interposed between said crown-pieces and the track-plates and adapted to afford independent lateral movement to the 80 axle-boxes, substantially as set forth.

8. The combination with a pedestal car-truck and its axle-boxes, of crown-pieces attached to the side frame in a direct vertical plane above the axle-boxes, track-plates secured to the tops of the axle-boxes, and rollers directly interposed between said crown-pieces and the track-plates, the opposed bearing-surfaces for such rollers having a curved or dished form adapted to afford lateral and 90 self-centering movements to the axle-boxes, substantially as set forth.

9. The combination with a pedestal car-truck and its axle-boxes, of crown-pieces attached to the side frame in a direct vertical 95 plane above the axle-boxes, track-plates secured to the tops of the axle-boxes and rollers directly interposed between said crown-pieces and the track-plates, the opposed bearing-surfaces for such rollers having a curved or dished form adapted to afford lateral and self-centering movements to the axle-boxes, and end flanges constituting stops, substantially as set forth.

10. The combination with a car-truck and 105 its axle-boxes of rollers interposed directly between the outer ends of the truck-frame and the top of the axle-boxes, said rollers being subjected only to a crushing strain between the truck-frame and axle-boxes, substantially as set forth.

Signed at Chicago, Illinois, this 17th day of July, 1901.

EDWIN S. WOODS.
